CLAIM

The ornamental design for toilet tank skirt, as shown and described.

DESCRIPTION

FIG. 1 is a perspective view of a toilet tank skirt showing my new design;

FIG. 2 is a left side elevational view thereof, the right side elevational view being a mirror image thereof;

FIG. 3 is a front elevational view thereof;

FIG. 4 is a lower left side perspective view thereof; and,

FIG. 5 is a cross-sectional view taken along line 5—5 of FIG. 4.

The broken line showing of the toilet in FIGS. 1-3 are for illustrative purposes only and forms no part of the claimed design.
